UNITED STATES PATENT OFFICE.

KNUT MARTIN DAHL, OF SAN FRANCISCO, CALIFORNIA.

OIL-BURNING FURNACE.

1,271,286.

Specification of Letters Patent.

Patented July 2, 1918.

Application filed December 15, 1913. Serial No. 808,738.

To all whom it may concern:

Be it known that I, KNUT MARTIN DAHL, a citizen of the United States, residing in the city and county of San Francisco, State 5 of California, have invented a new and useful Oil-Burning Furnace, of which the following is a specification.

It is the purpose of the present invention to devise a novel furnace especially adapted 10 for the burning of crude fuel oil and wherein provision is made to cause the temperature within the furnace to be raised to a sufficient degree to prevent the formation of carbon and the deposition of such 15 carbon on the walls of the furnace, and thereby increasing the efficiency.

It further consists of a novel construction and arrangement of a trap for the hot gases whereby the temperature of the furnace is 20 increased and a better combustion obtained.

It further consists of a novel construction and arrangement of a hanging bridge wall.

It further consists of other novel features 25 of construction, all as will be hereinafter fully set forth.

For the purpose of illustrating the invention there has been shown herein different forms thereof which disclose the broad principles involved, although it is to be understood 30 that the various instrumentalities of which the invention consists may be variously arranged and organized and that the invention is not limited to the exact arrangement and organization of these instrumentalities as herein set forth.

Figure 1 represents a sectional elevation of another embodiment of the invention, showing the same as employed in conjunction 40 with a water tube boiler.

Fig. 2 represents a section on line y—y Fig. 1, certain parts being omitted for the sake of clearness of illustration.

Similar numerals of reference indicate 45 corresponding parts in the figures.

Referring to the drawings the hanging bridge wall is illustrated as applied to water tube boilers. 19 designates the outer wall or casing which is provided with the furnace front 20 through which pass the fuel feeding devices 21, the burner of which discharges through the passage 22 in the front wall 23, said passage 22 communicating with the burner chamber 24 on one side thereof and with the combustion chamber 25. 26 50 designates the lining of the furnace which extends along the bottom thereof in union 55

with the vertical wall 27 from which latter extends the inclined brick wall 28 supported in any desired manner. 29 designates the hanging bridge wall embodying the invention and which in the present instance diverges slightly upwardly from the inclined wall 28, and is provided at its lower portion with a desired number of apertures or passages 30 therethrough. The tops of 60 the apertures or passages 30 are covered by brick arches 31. 32 designates a top wall whereby the products of combustion passing through the apertures 30 must pass first into the secondary combustion chamber 33 65 thence around the water tubes 34 and the baffle 35, thence around the baffle 36 and therefrom in the usual manner.

Since the other parts of the furnace are well known to those skilled in this art, it 70 has been deemed unnecessary to describe the same in detail. In the construction seen in Fig. 2, it has been deemed unnecessary to show in detail all of the tubes in section.

A trap for the hot gases is provided by 75 the bridge wall 29 so that such hot gases must pass through restricted apertures or passages, and it has been found in practice that by such construction and arrangement the temperature within the furnace is raised 80 to a sufficiently high degree to prevent the formation of carbon on the walls thereof.

It is to be understood that the hanging bridge wall as herein disclosed may be employed in conjunction with an internally 85 fired or other furnace and is especially adapted to furnaces for burning crude oil and furnaces with both the fire tube and water tube type of boilers.

It is also to be understood that the present 90 invention may be employed in conjunction with any desired or conventional type of fuel feeding means.

It will now be apparent that I have devised a novel and useful construction of an 100 oil burning furnace which embodies the features of advantage enumerated as desirable in the statement of the invention and the above description, and while I have, in the present instance, shown and described 105 the preferred embodiments thereof which have been found in practice to give satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:—

1. In a furnace of the character described, a burner chamber adapted to receive a burner having a fuel inlet, a combustion chamber, a wall between said burner chamber and combustion chamber having a passage therethrough for the admission of hydrocarbon to said combustion chamber, a depending bridge wall located at the rear of said combustion chamber and having a passage through its lower portion for the egress of the products of combustion, the upper portion of said bridge wall serving as a trap to retard a portion of the products of combustion, and a rearwardly inclined wall extending upwardly and rearwardly from the lower portion of said bridge wall thereby forming a secondary combustion chamber, whose walls diverge upwardly, said rearwardly inclined wall serving to deflect the products of combustion upwardly.
2. In a furnace of the character stated, a

combustion chamber, a burner chamber 25 adapted to receive a burner, a wall between said chambers having a passage therethrough for the admission of the hydrocarbon to said combustion chamber, a downwardly extended bridge wall and an arch 30 supporting the same, said bridge wall having a restricted passage in its lower portion, the upper portion of said bridge wall and arch serving to form a trap for the hot gases to prevent their direct passage from 35 the furnace, an inclined wall extending upwardly and rearwardly from the bottom of said bridge wall and forming a secondary combustion chamber located beyond said bridge wall and having upwardly diverging 40 walls, an upwardly extending rear baffle extending above said bridge wall, and a front depending baffle in advance of said rear baffle and overlapping the first named baffle.

KNUT MARTIN DAHL.
